US0D1108352S

(12) **United States Design Patent** (10) Patent No.: **US D1,108,352 S**
(45) Date of Patent: ** Jan. 6, 2026

(54) **CHARGING CASE**

(71) Applicant: **BIDI VAPOR, LLC**, Grant-Valkarie, FL (US)

(72) Inventors: **Jiatai Chen**, Shenzhen (CN); **Shengwen Zhou**, Shenzhen (CN); **Jian He**, Shenzhen (CN)

(73) Assignee: **BIDI VAPOR, LLC**, Valkarie, FL (US)

(**) Term: **15 Years**

(21) Appl. No.: **29/873,781**

(22) Filed: **Apr. 7, 2023**

(51) LOC (15) Cl. **13-02**
